UNITED STATES PATENT OFFICE.

WILLIAM J. HARKNESS, OF PITTSBURGH, PENNSYLVANIA.

DRILL-STEM COUPLING.

1,379,980.

Specification of Letters Patent.

Patented May 31, 1921.

Application filed July 6, 1918. Serial No. 243,552.

To all whom it may concern:

Be it known that I, WILLIAM J. HARKNESS, a citizen of the United States, residing at Pittsburgh, in the county of Allegheny and State of Pennsylvania, have invented new and useful Improvements in Drill-Stem Couplings, of which the following is a specification.

This invention relates to a joint and more particularly to a joint construction for drill stem sections and has for its primary object to provide a joint of a more substantial construction and one in which the parts are so associated that they will not become disconnected during the jarring operation of the stem.

An object of the invention is to provide a joint that may be quickly disconnected but capable of withstanding excessive shocks when assembled.

Besides the above my invention is distinguished in the use of a sleeve for covering the joint and accomplishing a more rigid construction and protecting the joint from the elements encountered in the use of the stem.

With these and other objects in view the invention will be better understood from the following detailed description taken in connection with the accompanying drawing wherein:

Figure 1 is a side elevation of the joint in assembled position.

Fig. 2 is a similar view in the opposite direction showing a sleeve that may be used with my invention.

Fig. 3 is a sectional view.

Fig. 4 is a side elevation of one section.

Fig. 5 is a side elevation of the other section.

Fig. 6 is a detailed view of a portion of the sleeve and its associate parts.

Figs. 7 and 8 are cross sectional views of the joint.

In the drawing I have shown one manner of carrying out my invention but at the start I wish to call attention to the fact that when putting the invention into practical use the outline or shape of the different parts may be changed to meet the requirements.

The upper drill stem section 1 is provided with an extension 2 shown in this particular instance as of a substantial rectangular configuration so as to snugly engage the walls of the slot 3 in the lower section 4. In this

construction it will be seen that the joint will be prevented from being disconnected in two directions by the engagement between the sides of the extension 2 and the walls of the slot 3. For the purpose of preventing the movement of the extension 2 as well as the section 1 in the remaining two directions, when the drill stem is in operation, I provide a pair of keys or lugs 5 on the lower section 4 that detachably engage correspondingly shaped slots 6 in the extension 2.

To complete the invention the extreme end of the section 4 is beveled as indicated at 7 so as to engage in the correspondingly shaped notches 8 in the upper section 1; thus it will be seen that the joint is reinforced in all directions.

When the joint is drawn from the well the upper section may be given an arcuate movement for disconnecting the joint, but this cannot take place when the stem is in the well as the side of the well will not allow the section to have the proper arcuate movement for disconnecting the joint. As will be noted more clearly from Fig. 3, the lower edges of keys 5 are beveled downwardly and outwardly. This permits the tongue or extension 2 of the member 1 to be rocked to the right as considered in this figure, a sufficient distance to break the joint. As will be readily understood, in practice there will be a very slight amount of unavoidable looseness or play between the parts of the joint which will be amply sufficient, in conjunction with the bevel of keys 5, to permit the joint to be readily broken in the manner stated.

It may be found advisable in practice to cover the joint and materially reinforce the same; and for this purpose I provide a sleeve 9 slidably mounted on the sections. One end of the sleeve 9 is beveled as indicated at 10 so as to engage in a tapering groove 11 in a collar 12 fixed to the lower section in any suitable manner. The sleeve is mechanically forced toward the collar 12 by a second collar 13 having a screw threaded engagement 14 with the upper section as clearly shown in Fig. 2. The sleeve is provided with slots 15 extending part way of its length so that the same may be contracted when the beveled end 10 thereof engages the groove 11 thereby throwing the sleeve into tight engagement with the exterior surface of the sections. Of course it is to be understood that the sleeve and its asso-

ciate parts may be constructed in various other manners than that shown.

From the foregoing description taken in connection with the accompanying drawing 5 it should be apparent that I provide a joint of simple substantial construction and one that cannot be disconnected during the operation of the drill stem; and further the joint is of such a construction that it cannot 10 work loose in the operation of the drill stem.

Having described my invention, what I claim is:

1. In a device of the character described, an upper section, a lower section, said sections being connected by a tongue and slot joint, a sleeve slidable on one of said sections and adapted to fit snugly about said joint, said sleeve being split from one end so as to permit ready adjustment thereof, 20 and means for securing the sleeve in position about the joint and for compressing said sleeve so as to force it into close contact with and about the joint.

2. In a device of the character described, 25 an upper section, a lower section, said sections being connected by a tongue and slot joint having means for preventing relative longitudinal movement of the sections, a sleeve slidable on one of said sections and 30 adapted to fit snugly about said joint, said

sleeve being split from one end, a member adjustable longitudinally of the section carrying the sleeve and in contact with the other end of said sleeve, and means carried by the other section adapted to engage the 35 split end of the sleeve so as to limit movement thereof, said means being also adapted to compress the sleeve so as to cause the same to grip tightly about the joint.

3. In a device of the character described, 40 an upper section, a lower section, said sections being connected by a tongue and slot joint having means for preventing relative longitudinal movement of the sections, a sleeve slidable on said upper section and 45 adapted to fit snugly about said joint, said sleeve being split from its lower end and having its lower end beveled downwardly and inwardly, a collar threaded on the upper section and in contact with the upper 50 end of the sleeve, and a collar secured on the lower section and having its upper end provided with a downwardly and inwardly inclined annular recess for reception of the lower end of the sleeve for limiting movement thereof and for compressing the sleeve 55 so as to cause it to grip tightly about said joint.

In testimony whereof I affix my signature.

WILLIAM J. HARKNESS.
